US0D1096019S

(12) **United States Design Patent** (10) **Patent No.:** **US D1,096,019 S**
(45) **Date of Patent:** **** Sep. 30, 2025**

(54) **ELECTRIC COFFEE PORTAFILTER CLEANER**

(71) Applicant: **GUANGZHOU CAFEMASY E-COMMERCE CO., LTD,**
Guangzhou (CN)

(72) Inventor: **Yuhua Liao**, Guangzhou (CN)

(**) Term: **15 Years**

(21) Appl. No.: **29/922,102**

(22) Filed: **Dec. 20, 2023**

(51) LOC (15) Cl. **15-05**

(52) U.S. Cl.

USPC **D32/1**

(57) **CLAIM**

The ornamental design for an electric coffee portafilter
cleaner, as shown and described.

DESCRIPTION

FIG. 1 is a perspective view of the electric coffee portafilter
cleaner showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view of thereof; and,

FIG. 8 is a bottom plan view of thereof.

The broken line portions are shown for illustration purposes
and form no part of the claimed design.

1 Claim, 8 Drawing Sheets
